INTERNAL COMBUSTION ENGINE CONTROL

Romeo M. Nardone, Westwood, N. J., assignor to
Bendix Aviation Corporation, South Bend, Ind.,
a corporation of Delaware

Application October 31, 1940, Serial No. 363,781

6 Claims. (Cl. 123—186)

This invention relates to internal combustion engines, and particularly to the control of the ignition of fuel in the combustion chambers of such engines.

An object of the invention is to provide means for preventing premature ignition of fuel in any engine cylinder during the starting period, that is, the period in which the engine is being rotated (cranked) by externally energized starting mechanism.

With the commonly used low speed starting mechanism, the cranking speed of an aircraft engine is too low to permit of sufficient ignition current generation by engine-driven means; and as the main magneto, or magnetos, of the engine are engine-driven, it follows that they are not effective at these low cranking speeds. This deficiency is ordinarily compensated for by providing auxiliary ignition current producing means, operable during the starting period, and not dependent upon rotational speeds for its effectiveness—an induction coil, for example, whose primary winding is fed by current from a storage battery, and whose secondary winding connects with the main distributor, through which it delivers a shower of high tension sparks at the several cylinder spark-plug gaps; but in order to guard against premature ignition the connection to the distributor is spaced from the main magneto connection by an amount that is sufficient to delay the spark until the piston has passed top dead center, whereas the main magneto connection results—when the speed becomes sufficient to develop any spark at all—in a spark occurrence slightly in advance of arrival of the piston at top dead center. While such advance firing of the fuel is desirable at normal running speeds, it is quite undesirable during the starting period, for at that period there is not sufficient momentum to continue the piston on its upward course, and there will result a reverse rotation, or "back-fire" of the engine. Such reverse rotation may seriously damage the starting mechanism; and the present invention has for an object the elimination of the possibility of such an advance spark during the starting process.

A further object is to provide means for rendering an advance spark impossible during starting, said means being so constructed as to assure production, of such advance sparks as soon as the starting process is completed.

A further object is to provide means for interlocking the ignition circuits with a circuit leading the starting (cranking) mechanism, where-

by the timing of the ignition sparks is made to depend upon whether or not the starting mechanism is operating; the timing being shifted automatically when the starting mechanism operation is discontinued.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing reference character 5 designates a switch housing of insulating material within which is an arm 6 rotatable on a spindle 7 at the center of the housing; the arm 6 being of current conducting material along its outer portion 8 but insulated from the spindle at its inner end. Also within housing 5 is a series of contact elements 9, 10 and 11, each of current conducting material, the first being engageable by arm 6 in one position of said arm, and the latter two being engageable by sector-shaped extension 12 of arm 6, as said arm is shifted about its axis of rotation by suitable means (not shown) projecting from the housing, and operable manually or in any other desired manner. These contact elements are adapted to receive conducting wires connected as follows: contact 9, a wire 14, to the induction coil 46—47, feeding the auxiliary rotating contacts 16 and 17 of the ignition current distributors 18 and 19, respectively; the latter being rotatable by gears or other parts driven from the engine crank-shaft, as are also the main magnetos 21 and 22; the said wire 14 also leading to the terminal post 23 of the starter 24, whose associated terminal post 26 is the terminus of the return feed 27 leading back to the negative side of the battery 28; contact 11, to the primary winding of main magneto 21; and contact 10, to the primary winding of main magneto 22; the use of "dual ignition" (two spark-plugs per cylinder) being assumed for the illustrated system, although of course the invention is applicable to single or triple ignition as well.

As above indicated the contact arm 6 is insulated from the spindle 7, and such insulation is indicated at 31 in the drawing. This insulation 31 permits the segment 8 to complete circuits, by way of battery 28 and contact strip 55 8, to the coil 46 and starter 24.

The extension 12 of arm 6 likewise is provided with two electrically distinct conducting segments 40 and 41 mounted on the extension 12, the latter being of insulating material. The spacing of the contact strips 40 and 41 is such as to cause them to have engagement at all times with the contacts 11 and 10, respectively, although in certain positions the engagement will involve the non-conducting ports 43, 44 and 45, the portion 43 being on the strip 40, and the portions 44 and 45 on the strip 41. All conducting portions of the strips 40 and 41 are grounded as indicated and therefore the associated magneto primary windings are grounded whenever the contacts 10 and 11, or either of them, are registering with a conducting portion of the strips 40 and 41; the grounded condition of the circuit being broken whenever the registry shifts from a conducting portion to a non-conducting portion.

In operation, the arm 6 is first rotated from the "at rest" or dead position, in which it is shown, and is caused to come to rest in the position designated "position A" on the drawing. In this position both the starter 24 and the auxiliary ignition circuit are energized, wherefore crankshaft rotation begins and igniting sparks occur in the several cylinders as the pistons therein pass slightly beyond top dead center, on their successive power strokes—this delayed firing being due to the trailing position of contacts 16 and 17, in relation to main magneto contacts 51 and 52, respectively, of the distributors. During this starting period the said contacts 51 and 52 are "dead," due to the "grounded" condition of the contact strips 40 and 41 on sector 12, said strips being then in circuit with the main magneto primary windings.

When the engine fires and starts to run under its own power, the operator will move arm 6 to position B, in which position both magnetos 21 and 22 will become operative simultaneously, due to the establishment of registry between the non-conducting portions 43 and 44 on the one hand, and the contacts 11 and 10, respectively, on the other, thereby interrupting the grounded connections of the primary windings of the magnetos, and thereby enabling their conventional circuit breakers (shown at 49 and 50, respectively) to function and cause current to be periodically induced in the secondary windings which feed the distributor contact arms 51 and 52, respectively. If it is desired that this shift from the auxiliary ignition circuits to the main magneto circuits be of an over-lapping nature as a safety precaution against a temporary hiatus in ignition current supply, the spacing of the non-conducting portions 43 and 44 may be made to have such a relationship to the spacing of the auxiliary ignition segment 9 that registry will be effected between said portions 43 and 44 and the contact pins 11 and 10, respectively, just prior to the breaking off of registry between segment 9 of arm 6 and the terminal edge of the strip 9; but of course, it will be understood that when the angular swing of the arm definitely reaches position B there will, of course, be a complete interruption of current flow to the strip 9 so that during the normal running of the engine, the ignition will be derived solely from the main magneto circuits, the distributor arms 51 and 52 of which will function to produce ignition in the several cylinders as the pistons therein successively approach top dead center on their respective com-

pression strokes. Thus there will be effected an automatic advance of the ignition point as compared with that which prevails during the starting period when the auxiliary ignition circuits rather than the main magneto circuits were functioning.

When the engine is to be cut out, the arm 6 will be returned of course to the dead position shown. Should it be desired to cut out one magneto, but not the other, arm 6 may be moved to position C or position D depending upon which magneto it is desired to cut out; such individual cutting out of magnetos being desirable on different occasions as, for example, to test the performance of one as against the other. When the arm is moved to position C, the sparkplugs associated with magneto 22 will be cut out, for in this position contact pin 10 will register with the grounded conducting portion 41 of the strip 41, while the contact pin 11 will register with the non-conducting portion 43 of the strip 40 and therefore the magneto 21 will continue to function. Conversely, in position D magneto 21 will cease to function due to the registry of pin 11 with grounded conducting portion 48 of strip 40; magneto 22, however, now being effective by reason of the registry of pin 10 with the non-conducting portion 45 of strip 41. The terminals 23, 26 of the starting unit may be the terminals of an electric motor constituting the prime mover of such a unit, or they may be the terminals of any other electrical starter control, such as the firing electrodes of a powder igniting device, where combustible powder is the source of starting energy (as in my Patent No. 2,207,936, granted July 16, 1940).

The induction coil assembly 61 is, of course, of conventional design and includes, in addition to the windings 46 and 47, the usual contacts 62 and condenser 63, all of which function in the usual manner (see Patent No. 1,214,555 to B. M. Leece).

What is claimed is:

1. The combination, with an internal combustion engine magneto, of engine starting means comprising a member for imparting initial rotary movement to the engine and an induction coil for facilitating ignition of fuel during operation of said member, and common means for controlling energization of both said starting means and said induction coil, said common means also acting to render said magneto ineffective so long as said member and induction coil remain energized.
2. The combination, with an internal combustion engine magneto and an advance-spark mechanism in circuit therewith, of engine starting means comprising a member for imparting initial rotary movement to the engine and an induction coil for facilitating ignition of fuel during operation of said member, and common means for controlling energization of both said starting means and said induction coil, said common means comprising a switch mechanism which also prevents energization of said magneto during the starting period, thus preventing premature passage of current to said advance-spark mechanism, and consequent reverse rotation of the engine.
3. The combination, with an internal combustion engine, of separate starting and running ignition circuits therefor, a starting motor for facilitating starting of the engine, an energization circuit for said starting motor, and common

means for preventing simultaneous energization of all said circuits.

4. The combination, with engine starting mechanism, of ignition circuits for said engine, said circuits including a pair of engine-driven current distributor elements and stationary contact elements successively engaged thereby, but at different times corresponding to different points in the engine's power cycle, and means for controlling said starting mechanism and ignition circuits in such manner as to prevent flow of ignition current to both said distributor elements simultaneously.

5. The combination with engine starting mechanism, of ignition circuits for said engine, said circuits including a pair of engine driven current distributor elements and stationary contact elements successively engaged thereby, but at different times corresponding to different points in the engine's power cycle, and means for controlling said starting mechanism and ignition circuits in such manner as to cause the ignition current to flow, first, through one of said distributor elements and then through the other, to vary the ignition timing in accordance with the setting of said controlling means, said last-named means including a switch mechanism

which, in one position, causes energization of said starting mechanism and one ignition circuit, and in another position causes deenergization of said starting mechanism and said one ignition circuit, while simultaneously causing energization of another of said ignition circuits, wherein the timing differs from that of said first-named circuit.

6. The combination, with an internal combustion engine magneto, of engine starting means comprising a member for imparting initial rotary movement to the engine and an induction coil for facilitating ignition of fuel during operation of said member, and common means for controlling energization of both said starting means and said induction coil, said common means comprising a switch mechanism which also controls energization of said magneto, and said switch mechanism including a plurality of stationary contact segments and a single rotatable contact member engageable selectively therewith, and means for supporting said segments in such spaced relationship as to prevent simultaneous energization of both said magneto and said induction coil.
